UNITED STATES PATENT OFFICE.

EDWARD E. ARNOLD, OF COVENTRY, RHODE ISLAND, ASSIGNOR TO THE NITROGEN CORPORATION, OF PROVIDENCE, RHODE ISLAND, A CORPORATION OF RHODE ISLAND.

CLOSURE FOR BARRELS AND THE LIKE.

Application filed June 14, 1923. Serial No. 645,328.

To all whom it may concern:

Be it known that I, EDWARD E. ARNOLD, a citizen of the United States, residing at Coventry, in the county of Kent and State 5 of Rhode Island, have invented certain new and useful Improvements in Closures for Barrels and the like, of which the following is a specification.

This invention relates to an improved 10 closure for barrels and the like which is adapted to be applied to or removed from a barrel or like container readily and without varying the position of the ends of the staves.

15 The usual wooden barrel as now constructed is made up of a series of staves having grooves formed on their inner faces for receiving the heads, which results not only in weakening the staves at the point 20 where the grooves are formed but also necessitates the loosening of the hoops and slight separation of the ends of the staves from each other in removing or inserting the head portion. This form of structure is partic- 25 ularly unfitted as a container for dry powdery material by reason of the fact that in inserting the head it is necessary to loosen the hoops and separate the staves which permits the powdery material to enter the inter- 30 stices between the staves if the barrel is nearly filled, thus causing considerable trouble in again drawing the ends of the staves together. Moreover, in the use of wooden barrels of the construction described it is 35 practically impossible to pack the material in the barrel so tightly as to entirely fill the same by reason of the difficulties in inserting the head and securing it in place. It is the purpose of the present invention to 40 overcome the difficulties above set forth by providing a metallic closure which can be placed in position or removed from the barrel without loosening the hoops or moving the ends of the staves, and which may 45 be so secured to the barrel end that it will be firmly held in place without the cutting away or otherwise weakening any portion of the staves.

50 Referring to the accompanying drawings:—

Fig. 1 is a side elevational view, partially

in section, illustrating one end of a barrel having my improved closure secured thereto.

Fig. 2 is a similar view showing a slightly modified form of the invention; and

Fig. 3 is a perspective view of the closure 55 illustrated in Fig. 2.

In the embodiment of the invention illus- 60 trated herewith 1 designates a barrel which may be formed from a plurality of staves, or may be built up of sheets of veneer suitably secured together or formed in any other suitable manner of appropriate material. In the embodiment illustrated in the drawings the barrel is formed of staves 2 65 which are in all respects similar to those now in general use except that the usual grooves formed upon the inner faces thereof adjacent the ends are omitted. A plurality of hoops 3 of wire, wood or metal strips may be em- 70 ployed for holding the staves securely in position relative to each other.

A hoop 4 of wood or metal surrounds the 75 staves adjacent to their ends and may be held thereon by friction but is preferably firmly secured thereto in any desired manner as by bolts, nails, or other fastening means. The provision of the hoop 4 of moderate thickness at the end of the staves forms with the lower outer surface of the barrel a circu- 80 lar recess or depression 5 located directly beneath the hoop 4 and extending about the barrel which is of reduced size in compari- 85 son with the outer circumference of the hoop 4 and the lower enlarged portion of the barrel. The provision of the recess or de- 90 pression 5 is accomplished in this manner without in any way weakening the staves as by cutting grooves therein. The closure 6 is of integral construction throughout and 95 comprises a depressed central portion 7 fit- 100 ing substantially closely within the open end of the barrel, and an upwardly extending annular groove 8 for the reception of the ends of the staves and the hoop 4.

The depressed central portion 7 of the closure may be provided with one or more annular corrugations 9 for the purpose of stiffening the closure, or if desired corruga- 100 tions may be formed therein radiating out- wardly from a point adjacent the center there- of. In fact the depressed central portion of

the closure may be corrugated or beaded in any desired manner as may be best adapted for imparting to the same the necessary degree of rigidity. The outer edge portion 10 of the closure which is formed to extend downwardly over the hoop 4 is preferably provided with a circular depression 11 adapted to fit within the recess or depression 5 and receive a wire or cable 12 which may be drawn taut and its ends secured together in any desired manner to prevent accidental removal of the closure.

removal of the closure. It will be seen that the above construction not only provides a form of closure which may be readily removed or replaced with a minimum expenditure of time and effort and that without in any way weakening the structure, but that when the wire or cable 12 is secured in place the hoop 4 is entirely enclosed, and the barrel cannot be opened without releasing the wire 12 the terminals of which may be sealed to prevent access to the contents of the barrel by any unauthorized person without the same being indicated by the breaking of the seal.

25 indicated by the broken line. In the modified form of the invention illustrated in Figs. 2 and 3, the barrel 1 is shown as formed of staves 2 in the usual manner which may be held together by 30 hoops 3. The staves 2 are surrounded by a hoop 4 adjacent to their free ends as in the form shown in Fig. 1, thereby forming a recess or depression 5 immediately below the hoop 4 which is of less circumferential extent than the outer surface of the 35 hoop 4. The closure 6 is provided with a depressed portion 7 fitting within the open end of the barrel which has corrugations 9 formed therein as in the structure shown in 40 Fig. 1. The outer edge of the closure 6 is bent downwardly to form an annular groove 8 for the reception of the ends of the staves and the hoop 4. In the form of the 45 invention as shown in Fig. 2, however, the downturned outer edge of the closure 6 has a plurality of slots 14 cut therein and extending upwardly from the edge thereof to a point adjacent the base of the groove 8 whereby greater flexibility is imparted to 50 the edge sections 15 of the closure, and less force is required to draw them closely against the outer surface of the barrel and hoop 4 and into the recess 5. Each of the edge sections 15 is curved slightly at the 55 point where it engages the recess or depression 5 as indicated at 16 whereby it readily springs into the recess or depression 5 when placed in position on the barrel and fits closely against the lower edge of the hoop 4 60 to provide a depression for the reception of the wire or cable 12 which is placed therein and drawn taut as in the embodiment illustrated in Fig. 1.

In each form of the invention as shown herewith, the opposite head of the barrel

(not shown) may be formed in the conventional manner or a closure of any desired type such as, for example, one of the forms illustrated, may be employed.

illustrated, may be employed. It will be understood that the forms of closure illustrated herewith differ from each other only in the provision of radial slots in the form shown in Figs. 2 and 3 which impart somewhat greater flexibility to the edge portion of the closure whereby, when formed of exceptionally heavy material, it may be more readily drawn into the groove or depression 5 by the wire or cable 12 and thereby secured against removal. In addition to the advantages attained by reason of the readiness with which the closure may be applied to or removed from a barrel or like container, its use permits the sealing of the container if desired and by reason of the portion 7 of the head being depressed the closure will not be readily punctured by the use of hooks in handling the container.

It is to be understood that by using the closure shown, and described herewith the barrel may be repeatedly refilled and the closure used repeatedly since the removal and reapplication of the closure to the barrel may be effected repeatedly without injury to the closure or the barrel. The closure may be made of any suitable metal, and may if desired be formed of galvanized or non-rustable material, and may be formed in any desired manner although the preferred manner of forming the same is by stamping with the suitable dies from metal in sheet form.

What I claim is:—

1. The combination with a barrel provided with a circular depression upon the outer surface thereof located adjacent to the open end of the barrel, a closure adapted to cover the open end of the barrel and having an edge portion extending over the depression in the outer surface of the barrel, and means for drawing the edge portion of the closure within the depression to hold the closure against removal. 105 110

2. The combination with a barrel provided with a circular depression upon the outer surface thereof located adjacent to the open end of the barrel, a metallic closure having a depressed portion fitting within the open end of the barrel and an edge portion extending over the depression in the outer surface of the barrel, and means for engaging the edge portion of said closure and drawing the same within the depression to hold the closure against removal. 115

4 against removal. 3. The combination with a barrel having 125
f a hoop secured to its outer surface adjacent to the open end thereof to form, with the
n outer surface of said barrel a circular depression extending therearound, a closure
130 formed of sheet metal adapted to cover the open end of the barrel and having an edge

portion extending over the depression in the outer surface of the barrel, and means for drawing the edge portion of the closure within the depression to hold the closure 5 against removal.

4. The combination with a barrel provided with a circular depression upon the outer surface thereof extending therearound and located adjacent to the open end of the barrel, an integral metallic closure covering the open end of the barrel and having a circular depressed portion fitting within the said circular depression, and means for holding the said circular depressed portion within the 15 said circular depression to prevent removal of the closure.
5. The combination with a barrel provided with a circular depression upon the outer surface thereof located adjacent to the open 20 end of the barrel, a closure for covering the

open end of the barrel and provided with an edge portion comprising a plurality of partially separated sections formed to engage the said depression, and means for holding the said sections in the depression to prevent 25 removal of said closure.

6. The combination with a barrel provided with a circular depression upon the outer surface thereof located adjacent to the open end of the barrel, a closure provided with a 30 depressed portion fitting within the open end of the barrel and having an edge portion comprising a plurality of partially separated sections adapted to overlie said circular depression, and means for drawing 35 the said sections into said depression and thereby holding the closure against removal.

In testimony whereof I have affixed my signature.

EDWARD E. ARNOLD.
